FIG.2

FIG.3

INVENTOR
William F. Waul

UNITED STATES PATENT OFFICE.

WILLIAM F. WAUL, OF ST. LOUIS, MISSOURI.

STEAM SYSTEM.

1,314,993.

Specification of Letters Patent. Patented Sept. 2, 1919.

Application filed December 2, 1918. Serial No. 264,951.

To all whom it may concern:

Be it known that I, WILLIAM F. WAUL, a citizen of the United States, and resident of St. Louis, Missouri, have invented certain new and useful Improvements in Steam Systems, of which the following is a specification.

This invention relates to improvements in a steam system, and has for its object a pipe 10 connection leading from the steam dome of the boiler or steam generator, the latent heat from the steam first passing through one or a plurality of machines without impairing its expansive properties, the said steam after 15 passing through these several machines being directed in a concentrator tank and from thence to the engine and the exhaust conveyed to the water heater or back to the boiler as found desirable.

20 The most essential and specific feature of my invention is to utilize the latent heat of live steam before admitting it into the engine without impairing its expansive properties to any great extent.

25 The theory of my invention is to pass live steam from the steam generator through one or a plurality of machines where heat is to be utilized thereby using the latent heat then passing the steam through a concentrator 30 chamber or separator by which any condensation is removed and the dried steam conveyed to the engine thereby saving a great percentage of fuel in operating a plant, and also dispensing with nearly all of the exhaust.

Figure 1, is a diagrammatic view showing the general connection of my invention.

Fig. 2, is a detail central vertical sectional view of the concentrator tank or separator 40 used in connection with my invention.

Fig. 3, is a horizontal sectional view of the same taken on the line 3—3 of Fig. 2, viewing the same in the direction indicated by the arrow.

45 Referring to the drawing in detail and especially to Fig. 1, 4 indicates a boiler or steam generator which is equipped with the usual steam dome 5 to which is connected a steam pipe 6 which is directed to any convenient place in the premises and to which 50 is connected steam pipes 7, 8, and 9 leading into various machines such as a drier 10, a washer 11 and a mangle 12, these machines being preferably used in establishments such as laundries or the like. From

these machines the live steam is directed into a pipe 13 through the connections 14, 15 and 16. This pipe then terminates into a concentrator or separator 17 which is preferably in the form of a drum as that indicated in Fig. 2, the pipe 13 entering the top as that shown in Fig. 2 and represented by the numeral 18. This drum is also provided with a depending tubular member or thimble 19 of somewhat larger diameter 65 than the end of the pipe 18 extending therein. Into the head of the concentrator or separator extends the end 20 of the pipe 21, which directs the live steam into the engine cylinder 22. This steam after entering the 70 cylinder of the engine permits the exhaust to escape through the pipe 23 and is directed into the feed water heater 24 which is of the ordinary construction and is provided with the usual water supply of a cool nature and 75 which is heated by means of the exhaust contacting therewith and from said water heater the heated water is conducted by means of pipe injector or the like back into the boiler.

At the bottom of the separator is connected a pipe 25 which leads to a pump 26 and any condensation accumulating in the separator is removed therefrom by means of the pump 26 and forced back into the boiler 85 through the pipe 27, such condensation being generally at a degree of from 280 to 300 degrees Fahrenheit.

As an additional safe-guard I connect to the pipe 25 a by-pass 28 provided with a valve and operating said pipe leading into the feed water heater.

To said pipe 25 is also connected a by-pass 29 leading into a steam trap 30 from which the condensation or particles of steam located therein is directed to the feed water heater through the pipe 31.

Such condensation which occurs in the separator is handled by the pump 26 but in the event of a mishap to said pump the condensation may be passed into the feed water heater by means of the steam pressure in the concentrator or separator passing through the by-passes 28 and 29 depending on which one of the two is in operation at that particular period.

The steam trap 30 shown in Fig. 1 and in connection with the system is ordinarily in readiness to be used automatically in the event the pump should be out of order, but

should the steam trap become water-logged then the condensation can be handled by means of the pass 28 by operating the valve located on said pipe.

5 Referring to the sectional view of Fig. 2 the concentrator or separator is of such structure as to permit the steam after having passed through the various machines to be separated from the moisture and as it 10 strikes the tubular member or thimble 19 this will permit the condensation to drop downwardly into the bottom of the separator and allow only dry live steam to pass upwardly into the end 20 of the pipe 21.

15 The essential feature or specific object is to pass live steam through one or a plurality of machines where heat is necessary and by so doing the latent heat of the live steam is utilized and said steam is directed to the 20 engine after having accomplished this purpose and said steam used with perfect efficiency without impairing its expansive properties to any great extent and by so doing provides a great saving of fuel in maintaining 25 a plant.

Having fully described my invention, what I claim is:

30 1. A steam system comprising a steam generator, a pipe leading therefrom, a plurality of machines to be heated, a return pipe, a separator to which the return pipe is connected, said separator separating the condensation from the live steam, a pipe leading from the separator conveying the live separated steam to an engine, and a means for conveying the condensation to the boiler, substantially as specified.

35 2. A system of the class described, comprising the delivery of live steam direct to a plurality of machines to be heated, directing the steam from the machines to a separator, and from thence to an engine, means for re-

45 moving the condensation from the separator and directing it to the boiler, and bypasses for handling the condensation in the event the pump is inoperative, substantially as specified.

3. A steam system comprising a steam generator, means for directing the live steam to machines and heating the same, a connection for directing the steam after it has passed through the machines, a concentrator in which the return pipe is connected and in which the condensation is separated 50 from the steam, a connection leading from the concentrator to the engine through which the purified steam is admitted to the cylinder of the engine and for receiving the exhaust from the engine, a pump connected to the concentrator for removing the condensation and directing it back to the steam generator, and a by-pass for handling the condensation in the event of the in-operativeness of the pump, substantially as specified.

65 4. A system of the class described comprising a means of conveying live steam into a plurality of laundry machines to be pre-heated, said steam after passing through the machines may be conveyed to a concentrator where the steam is separated from any condensation, the separated steam being then conveyed to the engine for operating the machines, and a means for returning the condensation back to the steam generator, substantially as specified.

70 In testimony whereof I have signed my name to this specification in presence of two subscribing witnesses.

WILLIAM F. WAUL.
